UNITED STATES PATENT OFFICE

FERNAND JOSEPH RHODES, OF PARIS, FRANCE

MOSAIC ARTICLE

Application filed September 27, 1926, Serial No. 137,870, and in Italy October 3, 1925.

The present invention relates to materials used in the mosaic industry and more particularly to the manufacture of tiles and other elements used in forming mosaic designs.

5 One of the objects of the invention is to provide improved tile elements having curved outlines, said elements being capable of being combined to give an indefinite number of designs.

10 Another object is to provide mosaic elements which will have the following characteristics: (a) juxtaposability with one another irrespective of size; (b) absence of angles sufficiently acute to render their use as 15 a material of construction impractical; (c) diversity of angles in each element, each angle having a definite relation to the others (60°, 90° and 120° are preferable); (d) periphery of size and contour to be combined 20 with one or more similar elements.

A further object of the invention is to provide mosaic elements which permits a maximum of ornamental designs to be produced with a minimal number of elements and 25 with a minimum of elements of different size.

The fundamental geometric principle upon which the method of outlining the mosaic elements is based is the same as that disclosed in French Patent No. 530,729, 12th October 30 1920, to the same inventor and consists in combining elementary curves outlined on a tile so that the radii employed are a function of

nite number of ornamental designs. In the present invention, the elementary tile is not square, or even rectilinear, but has limiting edges which are curves formed by one or several arcs of circles. The contours of these elements are designed so as to permit the elements to be combined in various ways to yield any number of decorative outlines.

The various objects of the invention are obtained by means of the procedures illustrated in the accompanying figures in which:

Fig. 1 represents a "fundamental" square tile upon which are described 8 arcs of circles.

Figs. 2 to 10 show various forms of blocks.

Figs. 11 to 19 illustrate a limited number 60 of many possible decorative combinations obtained by juxtaposing the blocks in various ways.

Referring to Fig. 1, there is shown a central square (in solid lines) surrounded by 8 squares (in dotted lines) which serve as a pattern for laying out a family of curves intended to be used in constructing a finished tile. Using the peripheral points of contacts of the assembly of squares as centers (points 70 indicated by small complete circles) a series of arcs are struck off having a radius equal to the diagonal of any square. Thus curve D, E₁ is obtained by striking off an arc from the lower right hand corner of the square in 75 the middle of the lowest row of squares as a center. If the side of any square is taken as unity, this diagonal has a length equal to

35

 $\sqrt{2}$

times the length of one side, said curves having their centers on the sides, or on the diagonals of any given tile, on the sides or diagonals of the tiles adjacent to the latter, or on the prolongation of any of the above enumerated sides or diagonals. In the prior patent, however, arcs of circles or the surfaces limited by said arcs were used to decorate a square tile. The juxtaposition of 40 45 these tiles in various ways yielded an indefi-

 $\sqrt{2}$

80

By striking off a series of such curves from the peripheral corners of the outer row of squares, curves C E₂, B H₂, A G₂, C H, etc., are obtained, points A, B, C and D representing the vertices of the central square and F₂, H₁, G₂, E₁, H₂, F₁, E₂ and G₁ the points of intersection of the various curves with the respective sides of the central square. Points I, K, L and M designate 85 90 points of intersection of the various curves

with one another. When it is desired to construct a decorative block any part or the whole of the arcs extending between the points shown in Fig. 1 are laid out on the articles to be cut to shape and the article is then formed to conform to this shape. Thus in Fig. 2, one side of the tile is formed by part of curve B L, another side is formed by curve A K, while the third side is formed of parts of curves L E₁, and K E₂, point E representing the intersection of the curves which if, extended, would terminate at E₁ and E₂, respectively. Figs. 3 to 10 show various forms of tiles composed in this way. It will be noted that, in each of these figures the characters, E, F, H and G have been used to designate points, which lie anywhere on the curves passing through E₁ or E₂, F₁ or F₂, H₁ or H₂, G₁ or G₂ respectively. Thus in Fig. 7, A F is part of the curve A F₁ (Fig. 1), A G corresponds to part of curve A G₂, etc., etc. As indicated on page 2, lines 11 and 12, the angles between the curves may be varied at will, but should bear a definite relation to one another. If desired, these angles may be chosen so as to correspond directly to the angle between two of the intersecting curves shown in Fig. 1. Thus, in Fig. 2, angle B L E corresponds to angle B L E₁ of Fig. 1 and angle A K E to angle A K E₂; in Fig. 3, angles H L E, E K F, F I G, may be laid out to correspond to angles H₂ L E₁, E₂ K F₁, F₂ I G, respectively; in Fig. 4 angle F K C corresponds to F₁ K C, angle G I D to G₁ I D, etc., etc. The various angles may be spaced off from one another by intercalating tangent curves as shown in Fig. 4.

Juxtaposition of blocks of various contours results in any one of ornamental designs shown in Figures 11 to 19. Figs. 11 to 14 show various color combinations of mosaics made up of tiles of the type illustrated in Figs. 7 and 9. Figs. 15 and 16 are the result of combining the blocks shown in Figs. 3, 4 and 8. Figs. 17, 18 and 19 are made up of elements having the shapes shown in Figs. 2, 3 and 10. In each of these figures the various numerals refer to tiles having the form shown in the figures designated by said numerals.

The simplest and easiest basis for forming the contours of the elements is by making use of arcs of circles all having a radius equal to the length of the side of the "fundamental" square multiplied by the square root of two and by displacing the center of each arm of the curve relatively to the sides, the diagonals and the corners. The above procedure was employed in connection with the tracing of the various above described forms. It is to be understood, however, that the mosaic elements may be made up of systems of curves having different radii and common tangents. When thus formed, the blocks can-

not be juxtaposed at all parts of their contours, but must be combined along limited portions thereof. This disadvantage, as compared to blocks formed on curves having a single radius, is counterbalanced by the increased number of combinations which may be obtained and by the correspondingly increased flexibility in the number of possible ornamental designs. This latter type of mosaic is particularly useful where the mosaic does not have to be constructed in place from the detached elements, but may be composed in the shop. In such a case, complete decorative combination made up to fit supports of fixed dimensions may be inserted intact into the supporting structures or the mosaic may be put in place by means of the usual operations of cutting and joining with an adhesive.

Obviously, the foregoing methods of outlining mosaic designs is not to be considered as being limited to the use of any special material. It can be employed equally well with natural stone, brick, terra cotta, fayence, porcelain, enamel, wood, glass, linoleum, rubber, etc., etc. Various combinations of curves representing any desired grouping of curvilinear triangles and polygons may be laid out on a sheet of paper and the printed reproductions used as a skeleton for laying out colored ornamental designs. Thus uncolored prints showing the outlines of the curves represented in Figs. 17, 18 and 19 may be filled in with color to give the various ornamental patterns shown in the several figures.

The invention lends itself especially to the manufacture of inlaid linoleums, wherein the mosaic elements are stamped out with a die and joined to produce a mosaic design. It can, of course, be equally well applied to the ornamentation of carpets, rubber flooring and ordinary linoleum.

When it is desired to form a tile or mosaic element, 8, square elements and a central element are either laid out on a sheet of paper or actually placed together, and a series of arcs having a radius which is some function of

$$\sqrt{2}$$

times the length of one side of one element are struck off from any of the sides or diagonals of any one tile, or from the sides or diagonals of an adjacent tile, or from the prolongations of any of the above enumerated sides or diagonals. If the lay-out has been made on paper, any arc or arcs or portions thereof may be transferred in any way desired to a mosaic block intended to be formed in accordance with the invention, or these arcs or portions thereof may be used to lay-out a die (for cutting out linoleum or the like) or any other forming device having the shape of the mosaic elements it is desired to produce (see Figs. 2 to 10). The mosaic

element or die or other forming devices thus laid out may be cut or formed in any way desired. When the mosaic elements are finished they may be laid together along curves of common curvature to produce a variety of ornamental designs.

5 What I claim is:

A mosaic element comprising a block having limiting edges formed in part of a plurality of curves having common tangents.

10 In testimony whereof I have hereunto set my hand.

FERNAND JOSEPH RHODES.
